UNITED STATES PATENT OFFICE.

JAMES W. LOGAN, OF NEWARK, NEW JERSEY, ASSIGNOR, BY DIRECT AND MESNE ASSIGNMENTS, TO JENNY M. PAGE, OF NEW YORK, N. Y.

LIQUID-FUEL BURNER.

Application filed March 14, 1924. Serial No. 699,240.

My invention is directed to improvements in the construction, form and arrangement of the several parts of a liquid fuel burner of the gravity feed type, with the objects 5 in view of providing a portable burner which will be very simple, safe and effective and which will produce a clean flame with a maximum heat for the fuel consumed.

A practical embodiment of my invention 10 is represented in the accompanying drawings, in which

Fig. 1 represents the burner in side elevation.

Fig. 2 represents the burner in vertical 15 central section.

The burner, generally speaking, comprises a hollow casing with its gravity liquid fuel feed pipe and its gas escape flame pipe and a priming base forming a support for the 20 said casing.

The hollow casing has exteriorly convex- 25 ed top and bottom walls 1 and 2 forming a combined liquid fuel and gas chamber 3. This hollow casing is provided with an exterior annular flange 4 which is shaped to form an annular drip basin 5.

A hollow supporting base 6 is provided 30 with inner and outer uprising annular flanges 7 and 8 forming between them an annular priming basin 9. A drain pipe 10 communicates with the priming basin 9 a short distance above the bottom of the basin 35 so as to permit the basin to be filled to a predetermined point with the priming liquid and prevent a dangerous oversupply of the priming liquid remaining in the basin.

The hollow casing rests upon the inner 40 annular flange 7 of the base and the supporting upper edge of said flange is separated or scolloped as shown at 11 to provide spaces for the passage of air between the flange and bottom of the casing.

The chamber 3 in the hollow casing is supplied by gravity with the liquid fuel through 45 a pipe 12 which leads from any suitable source of supply, not shown herein, through a vertical portion, upwardly and centrally, into the bottom of said chamber.

A gas burner pipe 13 leads upwardly from 50 the top of the chamber 3 and its nozzle 14 is directed downwardly toward the convex top of the hollow casing for the double purpose of generating the gas in the chamber and as a heating medium. A hollow ex- 55 tension 15 of the gas burner pipe 13 pro-

jects a predetermined distance downwardly into the chamber 3, the bore of said extension being considerably larger than the bore of the gas burner pipe.

A convex flame spreading shield 16 is 60 spaced by the lugs 17 a predetermined distance above the top of the hollow casing, said shield being arranged in position to receive the direct impact of the flame from the nozzle 14 and thereby prevent the undue heating of the top of the hollow casing. An ear 18 is struck up from the periphery 65 of the shield 16 in position to direct the flame issuing from the nozzle 14 in such a direction as to prevent the flame from curving back onto the nozzle. This permits a 70 free flow of air to come in contact with the gas as it issues from the nozzle, thereby preventing the accumulation of carbon or other refuse thereon which would interfere with 75 the true direction of the flame.

It will be understood that the hollow extension 15 of the gas burner pipe 13 forms a pocket in the upper part of the chamber 3, thereby preventing the chamber from 80 filling up with the liquid fuel and the enlarged bore of this extension prevents the accumulation of carbon or other possible interference with the free flow of the gas 85 from the chamber into the gas burner pipe 13.

It is evident that various changes may be resorted to in the construction, form and arrangement of the several parts without departing from the spirit and scope of my 90 invention; hence, I do not wish to be limited to the particular embodiment herein shown and described, but

What I claim is:—

1. A gravity fed liquid fuel burner comprising, a hollow casing forming a combined liquid fuel and gas chamber, a liquid fuel feed pipe opening into the bottom of the chamber, a gas burner pipe leading from the top of the chamber and having its nozzle directed downwardly toward said casing, and a hollow extension for the gas burner pipe projecting downwardly a predetermined distance into the chamber, the bore of said extension being larger than the bore 95 of the gas burner pipe.

2. A gravity fed liquid fuel burner comprising, a hollow casing having convex top and bottom walls forming a combined liquid fuel and gas chamber, a liquid fuel feed pipe 100

100

110

- opening into the bottom of the chamber, a gas burner pipe leading from the top of the chamber and having its nozzle directed downwardly toward said casing, and a hollow extension for the gas burner pipe projecting downwardly a predetermined distance into the chamber, the bore of said extension being larger than the bore of the gas burner pipe.
- 10 3. A gravity fed liquid fuel burner comprising, a hollow casing having convex top and bottom walls forming a combined liquid fuel and gas chamber, a liquid fuel feed pipe opening into the bottom of the chamber, a 15 gas burner pipe leading from the top of the chamber and having its nozzle directed downwardly toward said casing, a convex flame spreading shield spaced from the top wall of the casing, and a flame directing element uprising from said shield, said gas 20 burner pipe having a hollow extension projecting downwardly a predetermined distance into the chamber, the bore of said extension being larger than the bore of the gas 25 burner pipe.
4. A gravity fed liquid fuel burner comprising, a hollow casing having convex top and bottom walls forming a combined liquid fuel and gas chamber, said casing having an 30 annular exterior flange forming an annular drip basin, a base having inner and outer uprising annular flanges forming an annular priming basin, the inner annular flange acting as a support for said hollow casing, and 35 suitable liquid feed and gas burner pipes for
- said casing, the gas burner pipe having a nozzle directed downwardly toward said hollow casing.
5. A gravity fed liquid fuel burner comprising, a hollow casing having convex top 40 and bottom walls forming a combined liquid fuel and gas chamber, a base having inner and outer uprising annular flanges forming an annular priming basin, the inner annular flange acting as a support for said hollow 45 casing, the top edge of said inner flange being shaped to provide air spaces between it and the bottom of the casing, and suitable liquid fuel feed and gas burner pipes for said casing, the gas burner pipe having a nozzle 50 directed downwardly toward said casing.
6. A gravity fed liquid fuel burner comprising, a hollow casing having convex top and bottom walls forming a combined liquid fuel and gas chamber, said casing having an 55 annular exterior flange forming a drip basin, a base having inner and outer uprising annular flanges forming an annular priming basin, the inner annular flange acting as a support for said hollow casing, the top edge of 60 said inner flange being shaped to provide air spaces between it and the bottom of the casing, and suitable liquid fuel feed and gas burner pipes for said casing, the gas burner pipe having a nozzle directed downwardly 65 toward said casing.

In testimony, that I claim the foregoing as my invention, I have signed my name this 19th day of February, 1924.

JAMES W. LOGAN.
